CHINA STAND

Philip M. Seymour, Ann Arbor, Mich.

Application October 22, 1953, Serial No. 27,288

Term of patent 14 years

(Cl. D80—9)

To all whom it may concern:

Be it known that I, Philip M. Seymour, a citizen of the United States, residing at Ann Arbor, in the county of Washtenaw and State of Michigan, have invented a new, original, and ornamental Design for a China Stand, of which the following is a specification, reference being had to the accompanying drawing, forming part thereof.

I claim:

The ornamental design for a china stand, substantially as shown.
